[57] CLAIM

The ornamental design for blender base portion, as shown and described.

DESCRIPTION

FIG. 1 is a front, left side and top perspective view of a blender base portion according to the present invention.

FIG. 2 is a front view of the blender base portion of FIG. 1.

FIG. 3 is a right side view of the blender base portion of FIG. 1.

FIG. 4 is a left side view of the blender base portion of FIG. 1.

FIG. 5 is a top view of the blender base portion of FIG. 1; and,

FIG. 6 is a bottom view of the blender base portion of FIG. 1.

The broken lines are provided in the drawings merely for illustrating the environment in which the invention is used.

The broken lines do not form part of the design sought to be patented.
